KNITTED FABRIC

Thomas Henry Jones, Woodthorpe, England

Application September 16, 1935, Serial No. 40,851
In Great Britain September 18, 1934

2 Claims. (Cl. 66—50)

This invention is for a method of knitting, and an object thereof is to provide a mode of knitting fabric which is resistant to ladders. Another object is to provide a mode of knitting a new open-work fabric.

The fabrics according to this invention are characterized in that the needle loops or certain of them are spread from the needle wales in which they are produced so that they overlap adjacent needle wales and have subsequent stitch loops in said adjacent wales drawn through them. Referring now to the drawings,

Figure 1 shows one form of fabric, according to this invention, and

Figures 2 to 6 show the stages in the production of the fabric illustrated in Figure 1, while

Figure 7 shows the cams at one feeding position in a circular knitting machine for producing the said fabric, the lines 2—2, 3—3, etc., corresponding to the needle positions shown in Figures 3 to 6.

In the fabric shown in Figure 1 there is at least one thread loop which is spread over two wales and in at least one of said wales extends through a needle loop of the same course and itself continues on to form a needle loop. This, numbering the odd wales F, H, etc., the even wales G, I, etc., the even courses 40 and the odd courses 41, in course 40 the odd needle loop 40F is distended sideways and is passed through the even needle loop 40G, after which it is continued on to form a needle loop 40fg. In the next course 41, the even needle loop 41G is drawn, not through the preceding loop 40G, but through the loop 40fg. The said loop 41G is spread sideways into the needle wale H, being there passed through a needle loop 41H and continued on to form a needle loop 41gh of a succeeding course.

This fabric is produced by a method of knitting which comprises forming a course of stitches on a line of needles, spreading the needle loop from one needle over the next needle also, drawing said spread loop through the needle loop already existing on the said needle and casting off the said existing needle loop over it, and forming a new course of stitches. It is preferred that in any one course the loops shall be spread, say, from each odd needle over the next even needle. In the next course embodying spread loops, the loops may be spread from odd to even needles in the same or opposite direction, or they may be spread from even to odd needles. Plain courses of stitches may be interposed between the courses incorporating spread stitches and the

spread stitches may be grouped to form patterned areas.

The stages in the production of the fabric by the aid of a needle having a lateral projection for distending the loops are shown in Figures 2 to 6.

It is preferred to employ a special knitting needle having at or associated with its stem a lateral projecting part of bevelled or tapering formation, which, when projected into a stitch loop, spreads the said loop laterally and by co-operation with an adjacent needle enables said spread loop to be received by said adjacent needle or if desired transferred to the same. Such needle is shown in Figures 2 to 6, in which figures it has been elected to illustrate a latch needle. It will be observed that some distance beneath the latch 23 the needle is provided at its front or hooked side with a part 25 that is also bent or cranked laterally to one side of the needle. This tongue, which is preferably somewhat curved in cross section (as distinct from being bent sharply at right angles) has its upper edge 25' inclined so that as the needle is raised, as shown in Figure 2, the loop 40F encircling the shank slides on to this part and is spread sufficiently to permit the next needle 24' to be projected upwards through it as is shown in Fig. 3. This loop 40F is, therefore, transfix by two needles.

In Figure 2 a needle 24 is shown raised to a position in which the loop 40F is distended on the projection 25. In Figure 3, the adjacent needle 24' is shown projected through the distended loop, but not to a height sufficient to clear the distended loop below its latch. Therefore, when this needle 24' descends as in Figure 4, it takes the thread of the loop 40F in its hook and draws a new needle loop 40fg from it through the preceding loop 40G of the same wale. This having been done, both needles are brought to feeding height as at Figure 5 and a new thread is fed into their hooks. Thereafter, they descend as in Figure 6 and from this new thread draw new loops 41G, 41F.

As before, the needles may be selected to make their various movements in any suitable manner, but it is preferred to employ two sets of needles differing in a physical characteristic such as length. Figure 7 illustrates a portion of the cam box for a circular knitting machine in which the needles of one set are longer than the needles of the other set, said cam box being therefore provided with an upper and a lower cam race. At one feeding position, the short needles 24 are

raised by a cam 43 until at the line 2-2, they reach the distending position shown in Figure 2. Immediately afterwards the long needles 24 are raised by a cam 44 in the lower cam race until at the line 3-3 they transfix the distended loops. Thereafter, the short needles are engaged by the cam face 45 and are lowered slightly to remove the distended loops from the projections 25, while the long needles 24' are lowered by a stitch cam 46 so that at the line 4-4, they have drawn new loops such as 40/g from the thread of the loops that they previously transfix. On approaching the next feeding position, these needles 24 are raised by a cam 47 until they reach the feeding height at the line 5-5, after which needles 24 and the needles 24' are lowered by the respective stitch cams 48, 49 to form new loops. At the next feeding position, cams such as 44, 46, 47, 49 are located in the upper race, while cams such as 20 43, 45, and 48 are located in the lower race so that the selection is reversed.

The methods described herein may be applied to various kinds of fabrics, such as plain, rib, interlock, and fabrics comprising two webs bound together by threads extending between their con-

tacting faces, and these fabrics may include fancy stitches such as tuck and held stitches.

I claim:—

1. A method of knitting which consists in forming stitch loops on needles, spreading at least one stitch loop from the needle on which it was formed onto an adjacent needle also, drawing the spread loop through the existing stitch loop on said adjacent needle and casting off said existing loop, and forming new stitch loops on the needles. 5

2. A method of knitting on a line of needles which comprises forming a course of stitches thereon, spreading the loops from certain needles to adjacent needles at one side thereof so that said adjacent needles hold two loops, drawing the 15 spread loops through the existing loops on said adjacent needles and casting off the said existing loops, forming a subsequent course of stitches on the needles, spreading the loops from certain needles to adjacent needles at the other side thereof so that said adjacent needles hold two loops, drawing the 20 spread loops through the existing loops on said adjacent needles and casting off the said existing loops, and forming a subsequent course of stitches on the needles. 25

THOMAS HENRY JONES.
